CHARLES SURPRISE, OF STOCKPORT, NEW YORK.

CARDING-MACHINE.

SPECIFICATION forming part of Letters Patent No. 761,427, dated May 31, 1904.

Application filed December 30, 1903. Serial No. 187,236. (No model.)

To all whom it may concern:

Be it known that I, CHARLES SURPRISE, a citizen of the United States of America, and a resident of Stockport, Columbia county, and 5 State of New York, have invented certain new and useful Improvements in Carding-Machines, of which the following is a specification.

My invention relates to carding-machines 10 for textile fibers; and it consists of a presser device combined with the doffer or any other moving card-surface of the machine in such manner as to press the card-teeth just in advance of the comb or other delivery of the 15 sliver and force the seeds, dirt, and other foreign substances down into the space below the points of the teeth and lodge them to let the "sliver" or fleece of cotton or other fibers come off the doffer or other card clean, while 20 the said foreign substances remain until the card is cleaned from time to time, as herein-after described, reference being made to the accompanying drawing, which represents end 25 views of the cylinder and doffer and transverse sections of the doffer-comb and of the presser of my invention.

A represents the card-cylinder, b the doffer, and c the doffer-comb, of an ordinary carding-machine.

30 Just below the comb I apply a presser d in suitable relation to the doffer for the teeth to run against it and be pressed back or down, as shown, so that the seeds, dirt, and other foreign substances will be forced back into 35 the space behind or below the fibers of the fleece and lodged clear of the teeth of the doffer-comb and free of the fibers of the fleece being combed or otherwise cast off, leaving it clean, such dirt and other matters remaining 40 to be removed from time to time when the doffer or other card is cleaned. This presser consists of a smooth rod or shaft, of steel or other hard substance, so set on the card-frame and adjusted in relation to the doffer as to 45 press the wire teeth slightly and force the seeds, dirt, or other foreign substances down below the points of the teeth, as and for the purpose before stated. It will be fixed adjustably toward and from the teeth for enabling 50 it to be shifted for proper adjustment.

The presser may be of cylindrical form and may revolve either by contact with the doffer or it may be geared in any approved way for causing rotation and may be run either faster or slower than the doffer or at the same rate 55 of speed, or it may be stationary. It may be made of any suitable material, and if stationary may have any approved form of cross-section and may be attached to any convenient part of the machine. Such a presser may 60 be applied to any of the card-rollers or to the cylinder itself with benefit; in fact, to any of the moving surfaces of the carding-machine having wire teeth.

Although the presser presses the fibers as 65 well as the seeds and dirt in, the valuable fibers more or less entangled with the teeth and with the sliver being combed off spring out again, all of them that are of use, while the seeds and dirt remain in. 70

The presser is carefully adjusted, so as to make the seeds just clear the teeth of the doffer-comb.

In practical use on several machines for 75 several months fifty to ninety per cent. more of refuse, according to quality of stock, has been taken out than from like cards running without such pressers, as was proved by comparing the weights of the respective wastes. In these comparative tests about an ounce a 80 day was taken from the doffer by the hand-card from the machine not having the presser, while from those having the presser from eight to twelve ounces per day have been taken. 85

When it is understood that the solid seeds, chips, scraps, and most of the dirt are taken out of the stock by the "duster" in the picking-room, yet the "dead-head" seeds or husks, with some fibers attached to them, escape the 90 duster and picker and go into the card and make frequent stops and breakages in the after processes—namely, the spinning and weaving—or if in the knitting-mill make holes in the finished web, often converting good "firsts" 95 into "seconds," bringing lower prices, it will be seen there are two economies—one in time and the other in the finished product.

What I claim as my invention is—

1. In a carding-machine, the combination 100

with any moving card-surface of such machine, of a presser adapted to press the teeth of the card and force the seeds, dirt and other foreign substances down into the space below 5 the points of the teeth for lodgment and retention free of the passing fibers.

2. In a carding-machine, the combination with the doffer-cylinder and the doffer-comb, of a presser adapted to press the teeth of the 10 card and force the foreign substances into

lodgment free of the fibers passing onto the comb.

Signed at Hudson, New York, this 1st day of December, 1903.

CHARLES X SURPRISE.
